(57) **CLAIM**

The ornamental design for a display screen with animated avionics graphical user interface, as shown and described.

DESCRIPTION

FIG. 1 is a front view of a display screen with animated avionics graphical user interface showing our new design; FIG. 2 is a front view of a second image thereof; FIG. 3 is a front view of a third image thereof; and, FIG. 4 is a front view of a fourth image thereof.

The appearance of the transitional image sequentially transitions between the images shown in FIGS. 1-4. The process or period in which one image transitions to another image forms no part of the claimed design.

The broken lines of uneven length show the display screen and form no part of the claimed design. The broken lines of even length illustrate portions of the display screen with avionics graphical user interface that form no part of the claimed design.

The oblique line shading in FIGS. 1-2 and the stippled shading in FIGS. 3-4 indicate a contrast in appearance.

1 Claim, 4 Drawing Sheets
